(57) **CLAIM**

The applicants claim the ornamental design for a combined container and lid for food products, as shown.

DESCRIPTION

FIGS. 1 is a perspective view of a combined container and lid for food products;

FIG. 2 is a perspective view of the design illustrating the lid separated from the container;

FIG. 3 is a left side elevation view of the design;

FIG. 4 is a top plan view of the design;

FIG. 5 is a front end view of the design;

FIG. 6 is a rear end view of the design;

FIG. 7 is a bottom plan view of the design;

FIG. 8 is a right side elevation view of the design; and,

FIG. 9 is a vertical cross-section view of the container of the design.
